CARD PUNCHING MACHINE

Edward J. Von Pein, Endicott, N. Y., assignor to
International Business Machines Corporation,
New York, N. Y., a corporation of New York

Application April 15, 1939, Serial No. 268,029

8 Claims. (Cl. 164—111)

This case relates to machines for punching records such as tabulating or statistical cards.

The invention has for an object the prevention of repeat punching on a record by the punching machine. This object, in relation to a machine in which the record is inserted by hand into punching position, involves the provision of means to compel the operator to remove a record after it has been punched and to insert a new record into punching position, before the next punching operation is permitted to take place.

The object, further, is to provide for the punching operation to be controlled by and to require insertion of a record into punching position.

The punching machine with which the present invention is concerned includes power means to effect the punching operation. In this connection, the invention contemplates the provision of a manual device effective to initiate operation of the power means only if the record to be punched is properly placed in punching position. Stated in another way, this object is to initiate punching operation under the joint control of a manual initiating device and of the record to be punched. It is proposed that this joint control be ineffective after the machine has punched the controlling record and to require a new controlling record to be inserted after each punching operation in order to enable the next punching operation to occur.

The power means for operating the punching mechanism is cyclically operated and the initiation of a cycle is effected by operation of the previously mentioned manual device; provided, however, that a new record has been properly inserted into punching position.

It may be stated, as a broad object, that the invention shall provide, in a cyclically operating recording apparatus, means to manually initiate a cycle by operation of a manual device but shall prevent such cycle even though the manual device be operated, unless a new record has been inserted in recording position.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 is a plan view, with the casing in section.

Fig. 2 is a section along lines 2—2 of Fig. 1.

Fig. 3 is a section along lines 3—3 of Fig. 2.

Figs. 4, 5, 6, and 7 are sections, respectively, along lines 4—4, 5—5, 6—6, and 7—7 of Fig. 1.

Fig. 8 is a detail sectional view of the card operated contact mechanism, with the parts in a different position than in Fig. 3.

Fig. 9 is a circuit diagram, and

Fig. 10 shows a portion of the card with the columns which are adapted to be punched by the punching mechanism.

The record or tabulating card T (Fig. 10) has parallel columns of index positions which may be selectively punched according to the well known Hollerith code to represent digits 0 to 9. The present machine is intended to punch a number into the first two columns only, the first column from the left being the tens denominational order column and the next or second column being the units order column, so that in Fig. 10 the punching of the two columns represents the number 79.

The machine for punching these card columns may be considered as divided into three main sections. Referring to Figs. 1 and 2 these three sections are: The actuating or power section A, the designation selecting section S, and the punching section P, all mounted on a base 10 and enclosed by a case 11.

The punching section (also see Fig. 3) includes a sub-frame 12 carrying a pair of guide studs 13 and 14 which pass through elongated slots of punch-carrying bars 15u and 15t to guide the punch bars for slidable movement in a horizontal direction. The punch-carrying bar 15u carries the means for punching the aforesaid units order column of card T while the bar 15t carries the punching means for the tens order column. The punching means carried by each bar includes a single punch pin 16 mounted on the carrying bar for vertical, slidable movement, and a coacting die opening 16'. Between the punch pin 16 and the die opening 16', the punch carrying bar is formed with a horizontally elongated card slot 15' to receive the card to be punched by the depression of the punch pin. Secured to the sub-frame 12 are the legs of a generally U-shaped bracket 18 of which the base, or upper portion joining the legs, comprises a flat plate portion 18' constituting a card support or card bed. Fastened to the card bed 18' are angular side guides 19 formed with horizontally extending portions to overhang the sides of the card resting on the card bed. The card bed 18' and guides 19 constitute a card chute.

The rear end of the card bed 18' is bent upwardly to provide a back stop 18a for the card. A front stop for the card is provided by a lug 20 formed on the sub-frame 12. Located between the front 5 end of the card chute 18'-19 and the front stop 20 are the two punch bars 15u and 15t, and the card chute is so disposed as to align the card supporting surface with the card slots 15' of the punch bars. Thus, the leading end of the card 10 inserted by the operator into the card chute passes through the card slots 15' and engages the front stop 20. The rear end of the card is engaged with the back stop 18a, while the sides of the card abut the side angles 19. The card 15 chute thus holds the card in definite position with respect to the punch-carrying bars 15u and 15t, with the long dimension of the card extending at right angles and the card columns extending in the same direction as the direction 20 of movement of the punch-carrying bars. With the card in the chute, the first or tens order column lies in the card slots 15' of the punch bar 15t, while the second or units order column is located in the card slot of punch bar 15u. The 25 card slots are of sufficient length to permit the punch bars to move with respect to the card to any one of ten differential positions, each position corresponding to one of the ten designations, 0 to 9. With a punch bar in "0" position, its 30 punching couple 16-16' is in line with the 0 index position of a card column; in the "1" position, the punching couple is in line with the 1 index position, and so on.

The positioning of the punch bars is controlled 35 by the designation selecting section S. The designation selecting section includes a pair of stepped disks 25u and 25t, respectively corresponding to the units and tens order. There are eight series of steps 25u' on the units order disk, each series having ten steps corresponding to the digits 0 to 9, as may be understood from Fig. 2. Coextensive with each of the series of steps 25u', the tens order disk 25t has a single step 25t'. Since there is one tens order step for 40 each of the eight series of units order steps, there are eight tens order steps, corresponding to the digits 0 to 7 of the tens order. Both the units and tens order disk are rigidly mounted on a shaft 26. Also rigidly mounted on the shaft 26 45 is an indicator dial 27 bearing the numbers 0 to 79 corresponding to the eighty different positions in which the selector disks 25u and 25t may be set to control punching of the numbers 0 to 79. The indicator dial 27 is formed with a notched 50 periphery, there being one notch for each position thereof to coat with an impositive spring-operated latch 28 to maintain the assembly on shaft 26 in adjusted position. To adjust the 55 shaft 26, the front end thereof projects externally of casing 11 and is provided with a hand knob 29. The tens order steps 25t' are of progressively decreasing radial height, with the 0 step being of the greatest height and the 7 step being of the least height. The units order steps 60 25u' of each series also progressively decrease in radial height with the 0 step being at the greatest radial distance or height and the 9 step being at the least radial distance. Since the two stepped disks move rigidly together, they may be considered as a selecting unit, each peripheral portion of which represents a different two order value depending on the steps 25u' and 25t' disposed within the peripheral portion. The 65 periphery of the units order disk 25u is adapted to be engaged by a feeler 30u fastened to the front

end of the units order punch carrier 15u, and the tens order disk 25t is adapted to be engaged by a similar feeler 30t fastened to the front end of the tens order punch carrier 15t. The value of the selector steps in control positions, in front of feelers 30u and 30t, is indicated by the number on dial 27 exposed through the sight opening 31. In Fig. 2, the 0 of dial 27 is exposed, denoting that the 0 step of the tens order disk is opposite the feeler 30t of the tens order punch carrier and that a 0 step of the units order selector disk is in front of the feeler 30u of the units order punch carrier. To adjust the designation selecting means to control the punching of number 79 (see Fig. 10) the operator need only turn knob 15 29 one step clockwise to bring the number 79 into view at sight window 31. This adjustment will position the 7 tens order step in front of the tens order feeler 30t and will position the 9 units order step, of the series subtended by the 20 7 tens order step, in front of the units order feeler 30u. Similarly, by adjusting the dial 27 in either direction to bring any desired number into view at the sight window, a tens order step 25t' corresponding to the digit of the tens order of the 25 selected number will be set in front of the tens order feeler 30t and a units order step 25u' corresponding to the digit in the units order of the 30 selected number will be set in front of the units order feeler 30u.

In the normal, rear, idle positions of the punch bars 15t and u, their feelers 30t and u are at clearance distance from the locus of the 0 steps of selector disks 25t and u. The punch bars are held in their idle positions by a restoring lever 35, the upper end of which has a stud 36 abutting the depending projections 37 of the punch bars. Springs 38 individually connected to the punch bars tend to advance them, but are unable to do so while the lever 35 is in its initial clockwise position (Fig. 2). Lever 35 is connected, through a link 39, with a follower arm 40 pivotally carried by a shaft 41 and which has a roller 42 engaging a cam 43 on the cam shaft 44 (see Fig. 4). In the home position of shaft 44, cam 43 by engagement with roller 42, holds the connected parts 40, 39 and 35 in normal positions, as indicated in Figs. 2 and 4. In the normal position of lever 35, its stud 36 maintains the punch bars in rear idle positions. During the one revolution cycle of shaft 44, cam 43 permits rocker arm 40 to move clockwise, link 39 to move to the right and lever 35 to move counterclockwise. These parts are actuated in these directions, when permitted by cam 43, under the influence of springs 38 acting through the punch bars, their projections 37, and stud 36 of lever 35. Consequently the punch bars 15t and u are advanced by springs 38 to follow stud 36 until the feelers 30t and u engage the selector steps 25t' and 25u' which are in control positions. Assuming, for example, that the selector disks are set in 0 position, then the 0 tens step and the 0 units step, of the series subtended by the 0 tens step, are in control positions in front of their respective feelers 30t and 30u. These steps will stop the advance of the punch bars when their feelers reach the 0 selector steps in control positions. This extent of advance of the punch bars is such as to position their punch pins 16 over the 0 index positions of the card columns. Similarly with any other selector steps in controlled positions, the punch bars will be arrested thereby with their punch pins over the index positions corresponding to the controlling selector steps. 75

- Thus, a punch bar will advance its maximum distance when a 9 step is in control position and will locate its punch pin 16 over the 9 index position. It may be understood from the above that the selector steps 0 to 9 control differential movement of the punch bars to locate their punch pins over the index positions of the card columns corresponding to the values of the steps in controlled position.
- After the punch bars have been arrested in differential, selected positions by the selector steps so that their punch pins 16 are positioned to punch the card columns with the selected designations, the punch pins are pressed through the card and into their coacting die openings 16' to punch the selected designations. The means for depressing the punch pins 16 includes a punch depressing bar 46 (see Figs. 2 and 3) which is carried by the cross piece of a bail 47 pivoted on a shaft 48 carried by the subframe 12. Connected to one of the arms of the bail 47 is a link 49 pivoted to one end of a bell-crank lever 50 which is connected at the other end to a link 51. Link 51 (see also Fig. 5) is connected to a lower arm 52 rotatably mounted on the aforementioned shaft 41 and which is provided with a roller 53 following the periphery of a cam 54 on the cam shaft 44. During the cycle of shaft 44, cam 54 rocks arm 52 counterclockwise (Fig. 5) which, through link 51, rocks bail crank lever 50 clockwise to lower the link 49. The link 49, during this action, rocks the bail 47 downwardly causing the bar 46 to strike the heads of punches 16 and force the punches through the card and into the associated die holes 16'.
- Cam shaft 44 is in the actuating section A and is provided near one end with a driven clutch disk 56 which pivotally carries the clutch pawl 57, adapted to engage with a driving ratchet 58 rigid with a gear 59. Ratchet wheel 58 and gear 59 are rotatably carried by shaft 44, and the gear is meshed with a gear 60 driven by a pinion 61 on the shaft 62 extending from the gear reduction box 63 in which is the gearing (not shown) driven by the motor M. The clutch pawl 57 is normally held disengaged from the teeth of ratchet 58 by engagement of the rear or tail end of the pawl with a fixed stud 64. In order to initiate a cycle of cam shaft 44, the operator depresses the key 65 (see Figs. 1, 2 and 6). The lower end of key 65 has a stud 66 engaged with the butt end of a rocker arm 67 which is connected to a spring 68. The spring 68 acts through the arm 67 to maintain the key 65 in normal raised position. Connected to arm 67 by link 69 is an arm 70 fastened to a shaft 71 to which is fast an upright arm 72. Arm 72 has a pin 73 engaging the lower edge of a pawl 74 which is pivotally carried by arm 72 by means of a stud 75 (also see Fig. 7). A spring 76 between the pawl 74 and arm 72 yieldably maintains the lower edge of pawl 74 engaged with pin 73. The nose of pawl 74 is latched over the horizontally bent tab 77 formed at the upper end of a lever 78. The tab 77 initially abuts the top of a projection 80 of a disk 81 fastened to cam shaft 44. Upon depression of key 65, the stud 66 thereof rocks the arm 67 downwardly causing link 69 to rock arm 70, its shaft 71, and arm 72 fastened to said shaft clockwise (Fig. 6). As arm 72 rocks clockwise, it carries pawl 74 to the right, and the pawl nose through its engagement with tab 77 rocks the lever 78 clockwise (Fig. 7) against resistance of a spring 82. As a result, the tab 77 leaves the projecting lug 80 of disk 81.
- A lever 83 has a roller 84 at its free end (see Fig. 1) coacting with the inclined edge of a cam disk 85 on cam shaft 44. A spring 86 connected to lever 83 urges the lever downwardly, causing its roller 84 to cam against the inclined edge of disk 85 so as to rock cam shaft 44 counterclockwise a small amount when tab 77 is released from lug 80 of disk 81 in the manner explained above. This amount of rocking of shaft 44 is sufficient to displace the tail of clutch dog 57 from the fixed stud 64 permitting the nose of the clutch dog to engage a tooth of the driving ratchet 58. Further, the front of lug 80 of disk 81 has moved in front of the tab 77 temporarily to prevent return movement of the lever 78. Still further, the high portion of cam 88 (Fig. 6) on the cam shaft has moved away from the lower end of a latch 89, permitting a spring 90 connected to the latch to rock its nose above the shoulder 91 of the key slide 65 so as to maintain the key slide in its manually depressed position until a cycle of shaft 44 has been completed. The pivot 92 of lever 78 is carried by an intermediate portion of a lever 93 which is freely mounted on the aforementioned shaft 71. When the lever 78 is in its normal position, with its tab 77 engaged by the stop of lug 80 of disk 81, then the carrier lever 93 is thereby maintained in upper position. When the lever 78 is released from lug 80, a spring 94 (Fig. 6) connected to carrier lever 93 is permitted to rock the latter lever downwardly causing an insulating stud 95 thereof to depress the upper spring contact blade 96 of a normally open switch 97 so as to close the switch. Switch 97 is in the motor circuit, but its closure is not sufficient of itself to complete the motor circuit. In order to complete the motor circuit, it is necessary that a card T be properly inserted in the card chute 18'-19 to close contacts 98 in series with switch 97 (see Fig. 9). Referring to Figs. 3 and 8, contacts 98 are carried by spring blades 99 and 100 fastened through insulation to the subframe 12 of the punch section. Spring blade 99 engages a roller 101 of insulating material, which is carried by the ear 101' of a member 102. The member 102 is formed with a vertically elongated slot 102' through which a fixed pin 103 passes. A spring 104, between pin 103 and pin 105 of member 102, urges the member downwardly, while the spring leaf 99 abuts roller 101 to urge the member 102 in a clockwise direction about the pin 103. In the normal, lowered, clockwise position of member 102, maintained by springs 99 and 104, the front edge 102a of the member extends completely across the depth of the card slots 15' of the punch bars 15u and t. In this position of member 102, when a card T is inserted in the chute, the leading edge of the card engages the edge 102a and forces the member 102 rearwardly to close switch 98, as indicated in Fig. 3. Referring to Fig. 9, when both the switch 97 of the actuating section A and the contacts 98 of the punching section P have been closed, in the manner described above, a circuit is completed through motor M as follows: From the + side of the supply line, through a magnet 107, contacts 98, motor M, switch 97, and to the - side of the line. This circuit energizes magnet 107 to close contact 107a, by-passing contacts 98. The motor circuit will now remain closed as long as switch 97 is closed. The opening of switch 97 occurs at the end of the cycle as disk 81 of the cam shaft moves to home position and its lug 80 engages tab 77 to raise lever 78 and thereby to raise the switch-operating lever 93.

The motor, having been set in operation, the driving ratchet 58 is now rotated and, through the clutch dog 57, already engaged therewith, imparts rotation to cam shaft 44. During rotation of the cam shaft, cam 43 causes the punches 16 to be set in differential positions determined by the selector disks. After this occurs, the cam 54 (Fig. 5) rocks follower arm 52 counterclockwise which, through link 51, rocks bell crank lever 53 clockwise (Fig. 2) to lower the link 49, causing bar 46 to depress the punches 16 to perforate the card columns with the selected designations. The return half of cam 54 has a low point 54a (see Fig. 5) which permits the follower roller 53 to move further inward than its home position. When the follower roller 53 is engaged with low point 54a, the link 49 of the punch operating means is raised above its home position. On link 49 is a pin 108 which is below the ear 101' of member 102. Below the card-engaging front edge 102a of member 102, the member is recessed to provide an angular notch 102b which normally lies below the level of the card slots 15', as indicated in Fig. 3. When link 49 rises above its normal return position, the pin 108 thereof strikes ear 101' of member 102 to raise the member bodily until its front edge 102a and the top of its notch 102b rise above the level of the card T in the card chute. As soon as the front edge 102a of member 102 rises above the card surface, the member is free to rock clockwise under the influence of spring contact blade 99 until the side of notch 102b abuts the card edge, as seen in Fig. 8, meanwhile permitting contacts 98 to open.

As the cam shaft 44 completes its one-revolution cycle, the tail of clutch dog 57 rides under the fixed pin 64 (Figs. 1 and 6) which cams the nose of the clutch dog out of engagement with driving ratchet 58 (Fig. 6). Cam 88 acts to release latch 89 from key slide 65 which thereupon rises under the influence of spring 68 acting through pivoted arm 67. The return of arm 67 brings parts 70, 72, and 74 back to normal positions, enabling the nose of part 74 (Fig. 7) to reengage the tab 77 of lever 78, which has meanwhile been returned to upper, normal position by the lug 80 of disk 81. As the lever 78 moved upwardly, it carried lever 93 with it, causing switch 97 to open and break the holding circuit of motor M. Magnet 107 (Fig. 9) drops its contacts 107a, and the motor circuit cannot be reestablished unless both switches 97 and 98 are again closed. The actuating section A is then in starting condition.

If the operator permits the card T to remain in the card chute after it has been punched during the cycle of operations just completed, the following depression of key 65 is ineffective to start a new cycle of operations. This is because contacts 98 (Fig. 8), which have been opened, cannot be closed again by member 102 which now has the top of its notch 102b sitting on the card. The card cannot be moved further to the right (Fig. 8) because its leading edge is stopped by the frame lug 20 and, therefore, the member 102 cannot be moved counterclockwise to close contacts 98, the closure of which is required, in conjunction with the closure of switch 97, to complete the motor circuit and start a new cycle of operations. In order to start a new cycle, the operator must remove the old card from the chute and then insert a card again in the chute. The removal of the old card permits spring 194 to lower the member 102, positioning

its edge 102a completely across the depth of the card slot 15' and its angular notch 102b below the card supporting surface of card bed 18'. Now, upon insertion of the next card, the leading edge thereof strikes the edge 102a of member 102 to move the member rearwardly for closing the switch 98. With switch 98 closed by insertion of a new card and switch 97 closed as a result of depression of key 65, the motor circuit is again established to effect a new cycle of operations.

While there has been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a machine of the class described; punches and dies for coacting to make a perforated record of indicia on a record sheet in punching position, automatic actuating means to cause coaction of the punches and dies to punch the record sheet, means to initiate operation of the actuating means including a contrivance operated by insertion of the record sheet into punching position, and means operated as an incident to the punching operation for placing the contrivance in a condition in which it is incapable of repeat operation by the record sheet after punching thereof has been completed, whereby the latter sheet must be retracted from punching position before the contrivance may return to condition for operation by the next insertion of a record sheet.

2. In a machine of the class described; punches and dies for coacting to make a perforated record of indicia on a record sheet in punching position, automatic cyclical actuating means acting during a cycle to cause coaction of the punches and dies for punching the record sheet, means to initiate a cycle of the actuating means including a normally open switch and a member operated by insertion of the record sheet into punching position for closing said switch, and means operated as an incident to the punching operation for moving the member with respect to said record sheet and switch to a position causing the switch to open, in which the member is incapable of repeat operation by the record sheet in punching position, after punching thereof has been completed.

3. In a machine of the class described; a punching couple including punches and dies for coacting to make a punched record of indicia on a record sheet in punching position, automatic actuating means to cause coaction of the punches and dies to punch the record sheet, a start device movably mounted on the machine, a contrivance operated by insertion of the record sheet into punching position, means jointly controlled by operation of the start device and operation of the contrivance for initiating operation of the actuating means, and means operated as an incident to the punching operation for placing the contrivance in a condition in which it is incapable of repeat operation by the record sheet just punched and requiring this sheet to be retracted from punching position to enable the contrivance to return to a condition in which it may be operated by the next insertion of a record sheet.

4. In a machine of the class described; a recording couple to make a record on a record sheet in recording position, automatic actuating means to cause recording operation of the recording couple to be effected, a manual start device movably mounted on the machine, a contrivance operated by insertion of the record strip into recording position, means controlled jointly by operation of the start device and by operation of the contrivance for initiating operation of the actuating means, means operated as an incident to each recording operation for restoring the start device to unoperated position, and means also operated as an incident to the recording operation for placing the contrivance in ineffective condition for repeat operation by the sheet in recording position after this sheet has been recorded on. 5
5. In a machine of the class described, a recording couple to make a record on a record sheet in recording position, automatic actuating means to cause recording operation of the recording couple to be effected, a manual start device, a contrivance operated by manual insertion of the record sheet into recording position, means jointly controlled by the start device and contrivance for initiating operation of the actuating means, and means automatically operated as an incident to the recording operation for rendering said contrivance ineffective for repeat operation by the record sheet in recording position after the recording operation and until the latter sheet is retracted by the operator from the recording position. 10
6. In combination; a recording couple to make a record on a record sheet, automatic operating means to cause recording operation of the recording couple to be effected, a manual start device, a switch closed by insertion of the record sheet into recording position, electrical means controlled jointly by the start device and the switch for initiating operation of the operating means, and means for automatically causing the switch to reopen and to remain open after the recording operation and until the operator removes the record sheet just recorded on from recording position and inserts a record sheet anew into recording position. 15
7. In combination; a recording couple to make a record on a record sheet in recording position, automatic actuating means to cause recording operation of the recording couple to be effected, a manual start device, contacts closed by operation of the start device, a switch closed by manual insertion of the record sheet into recording position, a circuit established by closure of the contacts and of the switch for setting the actuating means in operation, means operated by the actuating means for causing the switch to open, means also operated by the actuating means for causing the contacts to open after the recording operation has been completed, and means for preventing reclosure of the switch, while the record sheet last recorded on remains in recording position, whereby reclosure of the contacts by repeat operation of the manual start device is ineffective until the record sheet last recorded on is removed and a record sheet inserted anew into recording position. 20
8. In combination; a recording couple to make a record on a record sheet in recording position, automatic actuating means to cause recording operation of the recording couple, a manual start device, contacts closed by operation of the start device, a switch closed by manual insertion of the record sheet into recording position, a circuit established by closure of the contacts and of the switch for setting the actuating means in operation, a magnet energized by the circuit, shunt contacts closed by said magnet to by-pass the switch whereby the circuit remains closed until the first-mentioned contacts open, means operated as an incident to the recording operation 25
- for first causing opening of said switch, means operated by the actuating means for causing the first-mentioned contacts to open after the recording operation has been completed, whereby the circuit is opened and said magnet deenergized for 30
- causing the shunt contacts to reopen, and means for preventing reclosure of the switch by the record sheet last recorded on while this sheet remains in recording position and until a record sheet is inserted anew into recording position. 35
